STOVE FOR BURNING EITHER LIQUID OR
GASEOUS FUEL

Martell D. Ingram, Wichita Falls, Tex.

Application December 29, 1948, Serial No. 67,967

7 Claims. (Cl. 126—94)

1

This invention relates to improvements in stoves and more particularly to stoves which will burn either liquid or gaseous fuel through the same burner and without interchange of parts and without the addition of accessory parts.

Heretofore, stoves have been designed to burn either gaseous or liquid fuel, but such stoves could use one or the other of the fuels but not both with the same burner mechanism. These burners, generally speaking, have required separate passages for the different types of fuel, and changes had to be made in the burner, when the type of fuel used was changed.

In the present invention, the stove is so designed as to use either gaseous or liquid fuel interchangeably, without the necessity of any changes being made in the burner, in the fuel inlet or in the valve that is used to control the burner.

The primary object of this present invention is to provide a stove that will burn either liquid or gaseous fuel interchangeably and without the necessity of making any changes in the burner, the piping or the control valve.

Another object of this invention is to provide a stove burner which provides for the combustion of either liquid or gaseous fuel, either of which fuels may be easily and readily ignited without "pre-heating or generating" the incoming fuel.

Another object of this invention is to provide a stove that is simple in construction, efficient in operation, and easily regulated.

An embodiment of this invention is illustrated in the accompanying drawings in which:

Fig. 1 is an elevational view of the stove with parts broken away and other parts shown in section to illustrate the details of construction;

Fig. 2 is an enlarged, vertical sectional view of the burner with parts thereof shown in elevation;

Fig. 3 is a perspective view of a portion of the burner with a portion of the spreader broken away, and other parts shown in section; and

Fig. 4 is a top plan view of the stove.

With more detailed reference to the drawing the numeral 1 designates a tubular stove body, which body is substantially cylindrical in form and which has legs 2 which support said body the desired distance above the floor. The tubular body 1 is closed at its upper end by a head 3, which head 3 has a flue or pipe 4 in one side thereof to carry off the products of combustion. The pipe 4 has a damper 5 therein, which damper 5 is secured to an axial shaft 6, which shaft is rotatably secured within pipe 4. The damper 5 is regulated by a lever 7 secured to the shaft 6, so as to

2

control the draft passing upward through the pipe 4.

The head 3 has sliding doors 8 and 9 pivotally secured thereto in position to close openings 10 and 11 respectively, which openings 10 and 11 are formed within the head 3. The opening 10 is primarily an inspection opening, but also provides access to the interior of the stove for lighting the burner. The opening 11 has a tube 12 extending downwardly therefrom to a point a spaced distance above the burner dome 13.

The tubular body 1 has a bottom member 14 secured therein about the outer periphery thereof, and which bottom member has an opening 15 therein. An upstanding tube 16 is secured around the opening 15 in fluid tight relation, and which tube 16 extends upwardly a spaced distance and has a plurality of support members 17 attached to the upper end thereof, which members 17 extend outwardly therefrom to support a burner dome 13. It is preferable to have the upper surface of the burner dome convex and the under surface thereof concave. It is also preferable to have the pipe 16 a spaced distance below the under surface of the dome 13, so that an annular space 18 is defined therebetween, so that a predetermined amount of air may pass therethrough. The burner dome 13 is of such diameter as to present an annular opening 19 around the outer periphery thereof and the inner diameter of tubular stove body 1. This annular opening 19 presents a predetermined area to admit a given volume of air therethrough at the normal operating draft pressure. This is a fixed area and gives the proper amount of air to give the normal combustion to the fuel.

A fuel inlet pipe 20 passes upward through tubular member 16, through dome 13 and to a point interior of the combustion chamber of the stove.

The fuel inlet pipe 20 has a valve therein and admits fuel therethrough, through the valve 21 and to the outlet opening 22 positioned above dome 13. The upper end of pipe 20 is closed by a spreader plate 23, which spreader plate is positioned within downwardly extending tube 12. Slots 24 are positioned in the upper end of pipe 20 and connect with openings 22, which, with the openings 22, form an increased outlet area for the fuel in pipe 20, particularly gas, however, as the liquid fuel rises higher than the holes 22, it may also pass outward through slots 24 onto the upper surface of the dome 13, in the case of liquid fuel, or horizontally outward above the upper portion of dome 13, in the case of gaseous fuel.

Operation

The fuel, either liquid or gaseous, is directed from a suitable storage supply into and through pipe 20 and valve 21 to the upper end of pipe 20 and out through holes 22. In the case of liquid fuel, it flows out through openings 22 down onto the convex surface of the dome 13 where it spreads thereover in a thin film. A lighted match or torch may be inserted through opening 10 to ignite the fuel at the edge of the burner dome 13. The flame will quickly spread around the upper surface of the burner dome, but will burn with greatest intensity around the outer periphery of the dome 13, due to the air that passes upward through tubular member 15 and out through annular passages 18 and 19.

The air passing through this annular space also causes the flame to be drawn upward by the draft created by the flue 4. The air mixture to the burner may be further regulated by the door 9, which is in position to close or partially close to any desired degree, the exterior opening of down pipe 12.

The damper 5 may be utilized to further regulate or gauge the amount of draft to obtain the maximum efficiency of combustion.

It is to be pointed out that either gaseous or liquid fuel, such as gas, kerosene, diesel oil, or crude oil, can be burned in the stove without any interchange of parts and without changing the regulating valves, and that either type fuel will operate with a high degree of efficiency. This type of stove burner produces combustion of the fuel that is practically free from smoke or soot, with any type of fuel that is used.

The device operated as described gives an even distribution of heat against the lower portion of the wall of the tubular body 1, and the products of combustion rise upward therein, which results in the heating thereof, substantially throughout the length of said body to a uniform degree of heat, regardless of the type of fuel used.

By having the burner dome formed in a concave-convex, lens-like manner, and with the fuel discharging above the convex portion thereof, to flow downward over and around this convex surface to the edge thereof where it may be readily lighted or ignited by any suitable means for initial generating into a combustible mixture. After the fuel is generated into a combustible mixture, the pipe 20 is sufficiently warm, by focusing the heat, by the concave portion, onto the pipe 20, which insures proper temperature for the proper generation of the fuel, without causing coking or resulting in an accumulation of carbon within the fuel inlet pipe 20. The pipe 20 protrudes upward and has a fuel outlet positioned intermediate the lower end of the down draft pipe 12 and the upper surface of convex burner dome 13, so that the air coming in from two directions, directs the blaze outward against the body 1 of the stove to give uniform heating thereof. It is to be further pointed out that the air coming through opening 15 comes into direct contact with the underside of the burner dome 13 and is heated. The amount of air directed into the stove through opening 15 is proportioned in accordance with the annular passage 19; however, additional air may be introduced through opening 11, the amount of which may be gauged by the manipulation of sliding door 9 to give proper combustion to the particular fuel being used.

In the case of gaseous fuels, the fuel is regulated by the valve 21 to control the flow of the gas to a point above the convex dome 13 where the

gas is mixed with primary air drawn down through down draft pipe 12. After the initial mixing of the gas with primary air, further air is drawn in through annular space 19 to produce a higher degree of efficiency in combustion of the fuel and consequently a higher degree of heat for the amount of fuel consumed.

While the invention has been described in some detail for purposes of illustration, it is to be understood that changes may be made in the minor details of construction, without departing from the invention as claimed.

Having thus described the invention, what is claimed is:

1. A stove for burning either gaseous or liquid fuel which stove has a hollow casing, a plate secured in the lower end portion of said casing and forming a bottom therefor, said bottom plate having an air inlet tube secured therein and extending upwardly into said hollow casing, a non-reservoir cover plate having a downwardly depending outer edge, which cover plate is supported a spaced distance above the upper end of said air inlet tube, said cover plate being spaced from the walls of said hollow casing so as to define an air passage, a fuel inlet pipe passing upward through said cover plate and having lateral fuel outlet apertures formed therein a spaced distance above said cover plate, means for closing the upper end of said fuel inlet pipe, said hollow casing having the upper end thereof closed by a top plate, and means for venting said hollow casing.

2. A stove for burning either gaseous or liquid fuel which stove has a hollow casing, a plate secured in the lower portion of said casing and forming a bottom therefor, said bottom plate having an air inlet tube secured therein and extending upwardly into said hollow casing, a convex burner non-reservoir dome having a downwardly depending outer edge, which dome is supported a spaced distance above the upper end of said inlet tube, said convex burner dome being spaced from the walls of said hollow casing so as to define an air passage, a fuel inlet pipe passing upward through said convex burner dome and having lateral fuel outlet apertures formed therein a spaced distance above said convex burner dome, means for closing the upper end of said fuel inlet pipe, said hollow casing having the upper end thereof closed by a plate and means within said plate for venting said hollow casing.

3. A stove for burning either gaseous or liquid fuel which stove has a hollow casing, a plate secured to the lower portion thereof and forming a bottom therefor, said bottom plate having an air inlet tube secured therein and extending upwardly into the interior of said hollow casing, a non-reservoir cover plate having a downwardly depending outer edge, which cover plate is supported a spaced distance above the upper end of said air inlet tube, said cover plate being spaced from the walls of said hollow casing so as to define an air passage, a fuel inlet pipe passing upwardly through said cover plate and having lateral fuel outlet apertures formed therein a spaced distance above said cover plate, disc means for closing the upper end of said fuel inlet pipe, said hollow casing having the upper end thereof closed by a top plate, said top plate having a downwardly extending tube secured therein which tube extends a spaced distance above said first mentioned cover plate so as to direct air into close communication with said incoming fuel, and means for venting said hollow casing.

4. A stove for burning either gaseous or liquid fuel which stove has a hollow casing, a plate secured to the lower portion thereof and forming a bottom therefor, said bottom plate having an air inlet tube secured therein and extending upwardly into the interior of said hollow casing, a non-reservoir cover plate having a downwardly depending outer edge, which cover plate is supported above the upper end of said air inlet tube and spaced from the walls of said hollow casing so as to define an air passage, a fuel inlet pipe passing upwardly through said cover plate and having lateral fuel outlet apertures formed therein a spaced distance above said cover plate, means for closing the upper end of said fuel inlet pipe, said hollow casing having the upper end thereof closed by a top plate, said top plate having a downwardly extending tube secured therein, said plate on said fuel inlet pipe positioned within said downwardly extending tube and spaced therefrom so as to define an air passage therearound, which tube extends to within a spaced distance above said first mentioned cover plate so as to direct air into close communication with said incoming fuel, an adjustable closure for said downwardly extending tube for regulating the incoming air, and means for venting said hollow casing.

5. A stove for burning either gaseous or liquid fuel which stove has a hollow casing, a plate secured in the lower portion of said casing and forming a bottom therefor, said bottom plate having an air inlet tube secured therein and extending upwardly into said hollow casing, a convex burner non-reservoir dome having a downwardly depending outer edge, which dome is supported a spaced distance above the upper end of said air inlet tube, said burner dome being spaced from the walls of said hollow casing so as to define an air passage, a fuel inlet pipe passing upward through said convex burner dome and having lateral slotted fuel outlet apertures formed therein a spaced distance above said convex burner dome, disc means for closing the upper end of said fuel inlet pipe, said hollow casing having the upper end thereof closed by a top plate, said top plate having a downwardly extending tube secured therein, which tube extends into said hollow casing a spaced distance above said convex burner dome so as to direct air into close proximity with the incoming fuel, an adjustable closure for said downwardly extending pipe for gauging said incoming air, and means for venting said hollow casing.

6. A stove for burning either gaseous or liquid fuel having a hollow casing, a plate secured in the lower portion of said casing and forming

a bottom therefor, said bottom plate having an air inlet tube secured therein and extending upwardly into said hollow casing, a non-reservoir cover plate concave on its underside and supported a spaced distance above the upper end of said air inlet tube, said cover plate being spaced from the walls of said hollow casing so as to define an air passage and to focus radiation of heat from said concave surface on said air inlet pipe, a fuel inlet pipe passing upward through said cover plate and having lateral fuel outlet apertures formed therein, which apertures each comprise a substantially round portion and an upwardly extending slotted portion connected thereto, said apertures being a spaced distance above said cover plate, means for closing the upper end of said fuel inlet pipe, said hollow casing having the upper end thereof closed by a top plate, and means for venting said hollow casing.

7. A stove for burning either gaseous or liquid fuel having a hollow casing, a plate secured to the lower portion of said casing and forming a bottom therefor, said bottom plate having an air inlet tube secured therein and extending upwardly into said hollow casing, a non-reservoir cover plate concave on its underside and supported a spaced distance above the upper end of said air inlet tube, said cover plate being spaced from the walls of said hollow casing so as to define an air passage and to focus radiation of heat from said concave surface on said air inlet pipe, a fuel inlet pipe passing upward through said cover plate and having lateral fuel outlet apertures formed therein, each aperture being of greater width at one end than at the other end, said apertures being a spaced distance above said cover plate, means for closing the upper end of said fuel inlet pipe, said hollow casing having the upper end thereof closed by a top plate, and means for venting said hollow casing.
